UNITED STATES PATENT OFFICE.

WALTER CHIPPERFIELD, OF ROMFORD, AND WILLIAM EDWARD GARFORTH, OF SNYDALE HALL, NEAR PONTEFRACT, ENGLAND.

KINEMATOGRAPH APPARATUS.

1,073,395.

Specification of Letters Patent. Patented Sept. 13, 1913.

Application filed March 20, 1913. Serial No. 755,592.

To all whom it may concern:

Be it known that we, WALTER CHIPPERFIELD and WILLIAM EDWARD GARFORTH, subjects of the King of Great Britain, residing at Jap Villa, Errol Road, Romford, England, and Snydale Hall, near Pontefract, England, respectively, have invented certain new and useful Improvements in Kinematograph Apparatus, and of which the following is a specification.

This invention relates to kinematograph apparatus, of that type in which a reel carries a number of flexible strips of material radiating therefrom, each strip having a picture arranged thereon; the reel is rotated and the strips are thereby successively exposed to the view of the observer, and it may be through a lens.

The present invention refers to the provision of an arm carrying a lip by which the leading picture strips are caught as the reel is revolved, brought to the exposure position, and past which lip the picture strips are flicked as the reel is revolved, the said arm being so fitted that it can be released from its acting position to permit of the removal of the reel and the placing into position of a new reel, and again accurately replaced in position for the operation of the new reel.

The invention also refers to the construction of the reel, whereby the picture strip, carrying the first picture of a series, is divided from the picture strip carrying the last picture of the series by a radially extending spring plate, the said plate holding the first

strips of the series at a less curvature than is normally assumed by the last strips of the series. With this arrangement when a reel has been little used the ends of the first

strips of the series are held by the spring plate, so that when the reel is revolved and the lip-carrying arm is in position, only the end of the spring plate and the first strips of the series will be engaged by the lip, and none of the pictures are exposed until the first of the series has contacted with the lip.

Beyond this the separation of the first strip of a series from the last strip by the spring plate provides a gap in the annulus of strips to receive the lip when the lip arm is thrown into the operative position, so that the strips are not damaged, and this is of importance since when a reel has been subjected to some considerable use the curvature of the strips may lessen, and then the lip might be forced

against the periphery of the strips and so cause damage.

The invention also refers to the arrangement and construction of the parts of the apparatus whereby economical manufacture is facilitated and to the mounting of the lenses when such are employed.

An example of construction of the invention is shown in the accompanying drawings, whereon,

Figure 1 is a side elevation of the apparatus, the reel having been removed, Fig. 2 is a front sectional elevation of the same apparatus, looking in the direction of the arrow A Fig. 1, and showing a reel in position and partly exposed. Fig. 3 is a plan view showing the framework supporting the upper lens.

Referring to the apparatus illustrated in the drawings, the base 1 is formed of cast iron or other suitable material of sufficient strength and weight to provide a firm support; the said base 1 is formed with an upstanding arm 2 to carry a spindle 3, Fig. 1, upon which is a worm wheel 4, from the forward face of which projects a pin 5 parallel with the axis of the said worm wheel. The worm wheel 4 engages a worm 6 on a shaft 7 revolvable in and carried by two upstanding lugs 8 extending from the base 1; the worm shaft 7 passes through a bush 9, Fig. 2, carried by one of the lugs 8, and the shaft is held in place by a pin 10 and at one end is fitted with a crank handle 11 by which it may be operated.

The reel is constructed with a central boss of any suitable form and is fitted, for instance, with two metal clamping plates 12, one of which is shown partly broken away at Fig. 2, and the boss is centrally bored at 13, Fig. 2, to slide onto the spindle 3, and is also formed with a bore 14, shown by dotted lines at Fig. 2, to receive the pin 5 as the reel is slid onto the spindle 3, so that the reel must revolve with the worm wheel 4, and between the clamping plates 12 are a number of strips 15 of flexible material, each strip 15 having a picture arranged thereon, and it will be observed that the strips are normally curved in the direction in which the reel is to be revolved.

In order to separate and expose the pictures on the strips 15 as the reel is rotated, a curved arm 16 is pivoted on a pin 17, which is simply slipped into a hole drilled

in a lug 18, Fig. 1, formed on the base 1. The curved arm 16, clearly shown in the drawings, is formed with a lip 19 adapted to engage the outer edges of the picture strips 15, when the arm 16 is in its operative position, as hereafter explained.

In order to retain the curved arm 16 it is fitted with a projecting pin 20, shown by dotted lines at Fig. 2, which pin engages a slot 21 in a pivoted plate 22, which is carried by a screw or pin 23 entering a hole in a lug 24 formed on the base 1.

The lip 19 of the curved arm 16, when the pin 20 is in the part of the slot 21, illustrated at Fig. 2, is adapted to engage the outer edges of the picture strips 15 in succession, and to temporarily hold the strips until by their own elasticity they can flick past the said lip.

When it is desired to remove the reel the slotted plate 22 is turned about its pivot until the pin 20 travels into the longer part of the slot 21, when the curved arm 16 falls away from the reel until it is arrested by the pin 20 reaching the outer end of the slot 21. In this position the reel can be removed and another one placed in position.

It is desirable when a fresh reel of pictures is placed upon the spindle 3, and the handle 11 is turned to revolve the reel, that none of the pictures shall be exposed to view until the first picture of the series has reached the exposure position; also it is desirable that the first strip of a series shall be distanced from the last strip and so a space shall be provided in the annulus of strips, into which the end of the lip-carrying arm can be entered. With this end in view, there is fixed in the boss of each reel, a spring plate which stands out radially, as indicated at 25 Fig. 2. This plate stands immediately in front of that strip 15 which is the first picture of the series, and the spring plate 25 supports the front strips so that they are at a less curvature than the last strips of the series, and consequently the ends of the front strips, supported by the plate 25, are at a greater distance radially from the center of the reel than are the succeeding strips. In consequence of this arrangement, when the reel is turned in the direction of the arrow, Fig. 2, the end of the plate 25 will spring past the lip 19 of the curved arm 16, and the said lip will catch the first strip of the series, and as the reel revolves the strips will flick past the lip in proper succession and exhibit the pictures as in motion. In the construction shown there is also fitted a second spring plate 26, Fig. 2, one end of which is fixed in the boss of the reel and the outer end is bent over, as shown, and presses against the rear strip 15 so as to maintain the rear strips in their curved positions.

The pictures so separated and exposed are preferably viewed through lenses 27, 28

carried in holders 29, 30, provided with lugs drilled to receive the rod 31, on which they are secured in the desired positions, by set screws. In some cases only one lens may be employed or both lenses may be omitted. The rod 31, is carried in the lug 32, by a set screw.

The holders 29, 30 consist of open frames having corner fillets 33, Fig. 3, on which the lenses rest; the edges of the lenses are beveled, as shown in the partial section at Fig. 2, and similarly there are correspondingly beveled faces on the holders; and pieces of india rubber 34 are inserted between the similarly beveled faces to hold the lenses firmly in position, the rubber being secured by adhesive material.

It will now be understood that to bring the apparatus into operation the pivoted plate 22 is lifted and the curved arm 16 permitted to swing out of range of the strips carried by the reel, by the pin 20 on the arm 16 sliding in the slot 21.

The already used reel is then removed and a new reel slid on to the spindle 3, and the curved arm 16 is then brought forward into the position shown at Fig. 2, and there held by the pin 20 entering the angled part of the slot 21.

If the reel has not been much used and the picture strips have consequently their full and normal curvature, they will not contact with the lip until the spring plate 25 is caught thereby, and so the first picture of a series will be exhibited in proper order. In cases, however, where a reel has been considerably used and consequently the strips have not their original curvature, the machine should be revolved until the gap in the strips, preserved by the spring 25, is opposite the lip of the curved arm 16, and then the curved arm can be thrown into its operative position. The apparatus is then operated by the handle 11 and the reel will be revolved in the direction of the arrow, Fig. 2, until the end of the plate 25 passes the lip 19 of the curved arm 16, and then the said lip will catch the end of the strip carrying the first picture of the series, and as the reel revolves the strips will successively pass the lip and each be exposed in its proper order.

It will be observed that the base 1 can be cast in one piece with all the necessary lugs which have been before mentioned, and when the necessary holes have been drilled all the parts can be easily assembled and the manufacture of the apparatus can therefore be economically carried out.

What we claim as our invention and desire to secure by Letters Patent is:—

1. In kinematograph apparatus: the combination with a base support, a spindle projecting from said support, a reel revolvable on said spindle, flexible picture-carrying

strips extending radially from said reel, and means for rotating said reel; of an arm pivoted at its lower end to said base support, said arm having a lip formed on its free end with which lip said strips are calculated to contact and flick past as said reel is revolved, and means for retaining said lip-carrying arm in said operative position and for releasing said arm and allowing it a limited retrograde movement away from said strips to permit of removal and replacement of said reels, substantially as set forth.

2. In kinematograph apparatus; the combination with a base support, a spindle projecting from said support, a reel revolvable on said spindle, flexible picture-carrying strips extending radially from said reel, and means for rotating said reel; of an arm pivoted at its lower end to said base support, said arm having a lip formed on its free end with which lip said strips are calculated to contact and flick past as said reel is revolved, a pin projecting rearwardly from said lip-carrying arm adjacent to the free end thereof, a plate, a pivot connecting said plate to said base support about which pivot said plate can have angular motion, said plate having a slot in its free end extending mainly in the direction of the length of said plate and also extending for a short distance at about right angles to the length of said plate, into the shorter length of which slot said pin on said lip-carrying arm enters to retain the lip of said arm in operative position, and into the longer length of which slot said pin is allowed to enter to permit and limit the movement of said lip-carrying arm away from said reel, substantially as set forth.

3. In kinematograph apparatus; the combination with a base support, a spindle projecting from said support, a reel revolvable on said spindle, means for rotating said reel, a number of strips of flexible material extending from the periphery of said reel and normally curved in the direction in which said reel is revolved, each of said strips on its concave curved surface having a picture, a spring plate standing out radially from said reel in front of the first picture strip of the series to separate said strip from the last strip of the series, said spring plate being calculated to hold the strips immediately behind it at a lesser curvature than the remainder of the strips; of an arm pivoted at its lower end to said base support, said arm having a lip formed on its free end with which lip said spring plate contacts as said reel is revolved to straighten out the first strips of the series and cause said strips to engage said lip and flick past same as said reel is revolved, and means for retaining said lip-carrying arm in said operative position and for releasing said arm and allowing it a limited retrograde move-

ment away from said strips to permit of removal and replacement of said reels, substantially as set forth.

4. In kinematograph apparatus; the combination with a base support having 70 lugs projecting therefrom, a spindle projecting from one of said lugs of said support, a worm wheel revolvable on said spindle, a reel revolvable on said spindle, and means to connect said reel to said worm wheel, a revolvable shaft mounted in bearings in two of said lugs projecting from said support, a worm on said shaft engaging said worm wheel, a crank handle on said shaft to operate same, and flexible picture-carrying strips extending radially from said reel and having a curvature in the direction of rotation of the latter, a picture upon the normally concave surface of each of said strips, a spring plate standing out radially 80 from said reel in front of the first picture strip of the series to hold out the first strips of said series and a second spring plate extending from said reel bent rearwardly to contact with the last of the series of said strips to retain same in their curved positions; of an arm pivoted at its lower end to said base support, said arm having a lip formed on its free end with which lip said strips are calculated to contact and flick past 90 as said reel is revolved, and means for retaining said lip-carrying arm in said operative position and for releasing said arm and allowing it a limited retrograde movement away from said strips to permit of removal and 100 replacement of said reels, substantially as set forth.

5. In kinematograph apparatus; the combination with a base support, a spindle projecting from said support, a reel revolvable 105 on said spindle, flexible picture-carrying strips extending radially from said reel, and hand-operable means for rotating said reel, an arm pivoted at its lower end to said base support, said arm having a lip formed 110 on its free end with which lip said strips are calculated to contact and flick past as said reel is revolved, and means for retaining said lip-carrying arm in said operative position and for releasing said arm and 115 allowing it a limited retrograde movement away from said strips to permit of removal and replacement of said reels; of a rod extending upwardly from said base support at right angles to the axis of said reel-carrying spindle, frames carried by said rod in planes at right angles to the axis thereof and located above the picture-carrying strips contacting with said lip, and magnifying lenses carried by said frames through 120 which to inspect said pictures.

6. In kinematograph apparatus; the combination with a base support, a spindle projecting from said support, a reel revolvable on said spindle, flexible picture-carrying 130

strips extending radially from said reel, hand-operable means for rotating said reel, an arm pivoted at its lower end to said base support, said arm having a lip formed on its free end with which lip said strips are calculated to contact and flick past as said reel is revolved, and means for retaining said lip-carrying arm in said operative position and for releasing said arm and allowing it a limited retrograde movement away from said strips to permit of removal and replacement of said reels; of a rod extending upwardly from said base support at right angles to the axis of said reel-carrying spindle, frames carried by said rod in planes at right angles to the axis thereof and located above the picture-carrying strips contacting with said lip, lips at the angles of said frames, magnifying lenses in said

frames resting on said lips, said lenses having inclined opposite edges and said frames having similarly inclined opposite projections, and india rubber blocks fixed between said facing inclined edges of said lenses and said frame projections, substantially as set forth. 20
